THREADING DIE

William J. Hogg, Cleveland, Ohio, assignor to The National Acme Company, Cleveland, Ohio, a corporation of Ohio

Application May 3, 1938, Serial No. 205,718

31 Claims. (Cl. 10—120.5)

This invention relates to threading tools and more particularly to pipe dies adapted for threading pipes such as oil well pipes usually of large diameter, the object of the invention being to provide an improved pipe die having automatically shiftable chasers or cutters for cutting a tapered pipe thread and which die is simple in construction and efficient in operation.

A further object of the invention is the provision of an improved die of the type specified in which the chasers or cutters are positively and, therefore, more efficiently controlled especially during their expanding movement, thereby ensuring that each chaser will do an equal amount of cutting and be prevented from pulling away from the controlling sleeve and take a heavier cut whereby a better tapered and smoother thread is obtained, and in which the die has a large range so that a number of different tapers can be readily obtained as well as a fine adjustment of taper by the mere manipulation of very simple adjusting means.

A further object of the invention is the provision of interchangeable chaser carrying members to permit the expansion of the die beyond the limits of its adjusting means to enable the die to cut an increased number of pipe sizes.

A further object of the invention is the provision of means for obtaining a fine adjustment of taper which is very advantageous in cutting work accurately since a great variation results in the threading of different materials and also in the feed of various machines.

A further object of the invention is the provision of means for permitting adjustment for length of thread without affecting the diameter of the threaded pipe at the point of opening of the die head.

A further object of the invention is the provision of means for adjusting the diameter of thread cut by the die without affecting the length or taper of thread cut.

A still further object of the invention is the provision of means for closing the die either from the inside or outside of the die head and also by means of a hand lever if desired.

In the drawings accompanying and forming a part of this specification, Fig. 1 is a side elevation of this improved die head.

Fig. 2 is a transverse section on the line 2—2 of Fig. 1.

Fig. 3 is a rear end view of the die.

Fig. 4 is a front end view of the die.

Fig. 14 is a detail in section of the guide opening for the yoke controlling pin.

Fig. 15 is an enlarged front view of the control lever housing showing in detail the adjusting means for various tapers.

Fig. 16 is a perspective view of the adjustable control block for the taper control lever.

Fig. 17 is a partial sectional view on line 17—17 of Fig. 3, illustrating the trip mechanism and also the emergency tripping means, and

Fig. 18 is a perspective view of the trip plate for tripping the die.

Similar characters of reference indicate corresponding parts in the several views.

Before explaining in detail the present improvement and mode of operation thereof, I desire to have it understood that the invention is not limited to the details of construction and arrangement of parts which are illustrated in the accompanying drawings since the invention is capable of other embodiments, and that the phraseology which I employ is for the purpose of description and not of limitation.

In the operation of this die, it is practicable to rotate either the die or the work and it is, likewise, practicable to feed either the die or the work but, in the present instance, I am describing the die rotating relative to non-rotatable work with the work advancing in accordance with the usual lead screw of the machine while the die is held against axial movement.

This improved die head, in the preferred form thereof, comprises a body 2 having a flanged shank 3 and pilot 4 adapted to fit into the spindle of the machine and this flange 3 is provided with a series of holes for facilitating the bolting of the die firmly to the spindles.

To the front end of the die body there is at

tached a ring-formed nose piece 6 of suitable diameter to provide for a large or small range of sizes of pipe or work as may be desired and the front face of this nose piece 6 is provided with removable hardened plates 7 to provide for inexpensive replacement when necessary.

The nose piece 6 is provided with a series of radial slots to receive die block slides 9 to which are secured the chaser holding blocks 10 carrying, in the present instance, a series of circular chasers 11, and the die block slides 9 are shifted inwardly and outwardly by a series of tongued cam rods 12 passing through openings 13 in the nose piece and slidably cooperating with any of a series of tapered cam slots 14 of the die block slides 9. This shifting movement of the die block slides 9 thus causes an inward and outward movement of the chaser blocks 10 and the chasers 11. These cam slots 14 will be referred to hereinafter in connection with the diameter adjusting means and the cam rods 12 will also be hereinafter referred to in connection with the taper control.

Within the die body is an inner slide member designated generally by 15, to the front end or extension 17 of which is attached an adjustable plate or ring 16 which will be designated herein as a trip plate in contradistinction to the tripping means hereinafter described. This extension 17 is secured to the front of the slide 15 by suitable screws 18.

Secured to the inner slide 15 and forming a part of the trip assembly is a member or block 19 held thereto by suitable screws 20 and dowels 21 and 22 (see Fig. 3). This member 19 carries two pins 23 and 24, one of which, 23, is used when threading $\frac{3}{8}$ " and $\frac{3}{4}$ " taper per foot of thread and the other, 24, of which is used when threading $\frac{1}{8}$ " taper per foot.

The illustrations show a die having a trip plate 16 set for threading a $5\frac{1}{2}$ " O.D. pipe with a short thread approximately $2\frac{3}{4}$ " long. On short threads of this type, the trip plate is moved backward under rapid traverse of the carriage until the pipe comes close to the chasers. The lead nut of the machine is then thrown in and the pipe is fed in the proper amount relative to the pitch of the thread being cut.

Taper control

The taper control for the die comprises a compound pivotal movement, one movement being obtained by a lever 25 pivoted at its outer end on an adjustable pin 26 so positioned as to remain at all times during the threading action in the same position relative to the axis of the die. The slot 26' permits the lever to move in an arc about this pin 26. The other end of this lever has a slot 27 adapted to slide on the pin 23.

As the trip plate 16, together with the inner slide and the member 19 carrying the pin 23, is moved back by the travel of the work during the threading action, the inner end of the lever 25 carried by the pin 23, which moves back parallel to the axis of the die, is caused to move back, the slot 27 permitting the inner end of the lever to swing in an arc.

Carried by this lever 25 is a stud 28 adapted to slide in a line parallel to the axis of the die in slots 29' of a block 53 carried by the body. Thus, the three pivotal points 23, 26 and 28 are at all times at the same distance from the axis of the die and any movement of any of these points during the threading action is parallel to the axis of the die and the stud 28 is caused to move back 75 in the ratio of the difference (the center dis-

tance) of 23 to 26 as (the center distance) 26 is to 28 which, in the illustration shown is a ratio of 4 to 1.

The other movement is obtained by a two-piece yoke 29 secured together by a ring 30 around the outside of the die and secured to the flanged face 30' of the yoke and carried by ribs 30" of the yoke (see Fig. 1). This yoke is adapted to be carried pivotally by a stud 31 extending through the yoke 29 and size adjusting blocks 32 hereinafter described.

At the opposite side of this yoke 29 is the stud 28 of the lever 25 so that, as the lever 25 is moved back and with it the stud 28, this opposite side of the yoke 29, likewise, will be moved back, thereby pivoting on the stud 31.

Midway between the studs 28 and 31 on each side of the yoke is located a pilot screw 33 and within the yoke 29 and exteriorly of the body 2 is a sliding sleeve 34 having a flanged head or ring 35, the pilots 36 of the pilot screws 33 being secured to this sleeve 34. Therefore, as the pin or stud 28 moves back with the pivotal action of the yoke 29 on the stud 31, these pilots 36 will be moved back one-half the distance of the stud 28 and with them the sleeve 34 will be moved back the same distance.

The cam rods 12 hereinbefore mentioned are secured to the head 35 of the sleeve 34 by any suitable means. These cam rods have a laterally extending inclined tongue to engage any of the cam slots 14 of the block slides 9. The angle of this tongue and that of the slots is eight times the angle of a $\frac{3}{4}$ " per foot tapered thread. Therefore, as the ratio of movement of the pin 23 to the stud 28 is four to one and the ratio of movement of the stud 28 relative to the pilots 36 is two to one, the movement of the sleeve 34 and cam rods 12 is one to eight relative to the inner slide 15. Thus, since the angle on the cam rods is eight times the angle of $\frac{3}{4}$ " to one foot taper, the die block 9, together with the chaser blocks 10 and chasers 11 will be expanded $\frac{3}{4}$ " per one foot as the pipe is fed into the die.

The pivot pin 26 is adjustable and can be moved outward sufficiently to thread $\frac{1}{8}$ " taper per foot and inward sufficiently to thread $\frac{3}{8}$ " taper per foot and, if necessary, to cut $2\frac{3}{64}$ " taper per foot.

When it is desired to cut a $\frac{1}{8}$ " taper per foot, it is merely necessary to substitute a longer lever 25' (see dotted lines, Fig. 6) for the lever 25 and use the stud 24 instead of the stud 23 and this gives a greater ratio between 24 and 26 relative to 28. In so doing, it is necessary to remove the stud 23 so as not to interfere with the long lever 25'.

Tripping mechanism

The tripping mechanism comprises a trigger 37 (see Figs. 7, 9, 10 and 17) shown as a curved member for the purpose of obtaining sufficient side bearing, fitted into a slot machined in the body 2 and pivoted to the body 2 by a pin 38 (see Fig. 7).

A spring 39 is located between one end of the trigger and the bottom of the slot in the die body 2 whereby this end of the trigger is held in engagement with a slot 40 in the adjusting and tripping block 41 whereby the trigger holds the block 41 from being forced back by the tension of the springs 42.

The chasers are opened at the end of the cut as follows:

The work in contact with the trip plate 16 moves the trip extension 17 together with the in-

ner slide 15 back in the die body whereupon a flat trip piece 43, secured to the inner slide by screws 44 (see Fig. 17) having at one end thereof a cam 45, is brought into contact with the end of the trigger 37 as at 46 at a predetermined time according to the length of the thread to be cut on the work. This contact of the cam 45 with the trigger 37 swings the trigger on its pivot whereby the opposite end of the trigger swings inwardly 10 and out of the slot in the block 41, thus permitting the block 41 to move to the rear of the die under tension of the springs 42, thereby to expand the chasers.

Emergency tripping mechanism

15 The die may also be tripped at any time by an emergency trip located in the shank of the die. For this purpose, a pin 65 (see Figs. 3, 10 and 17) having a beveled end 66 is located in the die shank 20 and is kept from turning by means of the pin 67 (see Fig. 3).

The beveled end of this pin 65 contacts the beveled end 68 of a spring pressed pin 69, the other end of which has a beveled end 70 in contact 25 with a beveled slot 71 in the side of the trigger 37. Pressure on the pin 65 causes it to move inwardly, thus forcing the pin 69 to move the trigger 37 outwardly, thus releasing the block 41 and so tripping the die.

Diameter adjusting mechanism

30 In the block 41 is fastened an adjustable block 32 that carries the pivot stud 31 of the taper control yoke 29. Since the die is designed to trip 35 when the automatic tripping means is at the same point each time, it will thus cut the same diameter of thread at the large end of the pipe even though the adjustment is changed for length of thread as hereinbefore described.

40 As hereinbefore described, the stud 31 forms the pivot point of the taper control yoke and does not move while the die is cutting the thread but when adjustment for diameter is required, this stud 31 is adjusted as follows:

45 For an increased diameter of thread, the screw 48 which may be graduated for fine adjustment if desired, is loosened and the screw 49 is tightened. This action causes the angular clamp 50 to be forced inwardly and the angular clamp 50' outwardly which, in turn, moves the adjusting block 32 rearwardly. When the desired rearward movement of this block has been obtained, the screws 48 and 49 are tightened, thereby locking the block 32 securely in place.

55 Since the stud 31 extends through the taper control yoke 29, movement of this adjusting block 32 rearwardly moves the stud 31 back together with the yoke 29, the pilot 36, sleeve 34 and cam rods 12 and as these cam rods 12 move back, the die blocks 9 together with the chaser blocks 10 and chasers 11, are moved outwardly and an increased thread diameter is obtained. If the screw 49 is loosened and the screw 48 tightened, a reverse movement of the adjusting block 32 is obtained, resulting in a thread of smaller diameter.

The aforementioned procedure is for fine adjustment from .0005" to $\frac{1}{16}$ " large or small.

Another adjustment for size is obtained by using the various slots 14 in the die block 9. In the particular illustration set forth, there are four of these slots 14, although any desired number may be used. If the tongues on the cam rods 12 are inserted in the slots of block 9 nearest the

5 center, a large diameter will be threaded with the same chaser blocks 10 and chasers 11. As each slot toward the outside of the blocks is used, a smaller diameter can be threaded. By the use of the fine micrometer adjustments of the screws 48 and 49 and the slots 14 in the die blocks 9 it will be noted that a large range of sizes can be threaded with a single set of blocks and chasers.

A change of size can also be obtained by the use of several sets of die blocks 9 or chaser blocks 10. By using various diameters of chasers 11 10 or by using holders for rectangular blades, further changes in size can be obtained.

Adjustment for taper

The adjustment for taper is controlled by moving the square-headed pin 26 toward the axis of the die for low taper adjustment and away from the axis of the die for high taper adjustment.

In the illustrations (see Figs. 6, 13 and 15) the short lever 25 connected with the upper pin 23 and pin 26 is for cutting a thread approximately $\frac{3}{4}$ " taper per foot. When a greater taper is desired, it is merely necessary to loosen the screws 51' sufficiently to permit this block 51 to be moved out on the adjusting block 53 to the 25 desired point, the mating serrations 52 in the blocks 51 and 53 serving to hold the blocks securely together when the screws 51' are tightened.

The two elongated slots 51" in the adjusting block 51 (see Fig. 16) permit this block to be 30 moved inwardly and outwardly to give a fine adjustment of taper. The taper can be adjusted plus or minus $\frac{1}{16}$ " to a foot.

If a $\frac{3}{8}$ " taper per foot is desired, the pin 26 can be moved to another hole 54 in the block 51 35 and the block moved so that this pin 26 will be closer to the axis of the die and a fine taper can be adjusted at this point to obtain $\frac{1}{16}$ " taper per foot plus or minus as hereinbefore explained by the adjustment of the block 51. By leaving the 40 pin 26 at this same point but substituting the longer lever 25' shown in dotted lines in Fig. 6 for the short lever 25 and using the pin 24 instead of the pin 23, a $\frac{1}{16}$ " taper per foot will be obtained and a plus or minus adjustment can 45 be had by moving the block 51 inwardly or outwardly. When using the long lever 25' the pin 23 used with the short lever will have to be removed as hereinbefore explained to prevent its interfering with the movement of the long lever. 50

While the foregoing provides for three tapers, it is obvious that many others may be obtained by the use of various spacings at the control points.

Adjustment for length of thread

55 When the longest thread that the die will make is desired, the inner slide is brought forward as far as possible and the trip plate 16 adjusted rearwardly by removing the screw 55 which allows the key 56 to be removed. This key 56 fits in a keyway in the threaded part 17 and in one or more slots in the trip plate holder 57. When the key is removed, the trip plate holder 57 together with the trip plate 16 can be adjusted rearwardly. If 60 so adjusted until the front face of the trip plate 16 comes in line with the front face of the chasers, the full expanding action takes place.

When the pipe or work is moved into the die, a longer thread can be cut if the trip plate is 70 further adjusted rearwardly whereby the chasers will cut the length of the chaser before commencing to expand.

The key 56 keeps the threaded part 57 from turning when the end of the pipe contacts the 75

trip plate 16 if either the pipe or die is revolving and the parts 57, 16 and 58 are so constructed that when the pipe is against the face of the trip plate 16, it can rotate with the pipe by having the nuts 59 tightened on the end of the part 57 rather than on the face of the trip plate 16.

Larger or smaller rings 16 can be made to suit the pipe being threaded since this ring must be larger than the hole in the pipe or work and smaller than the root diameter of the thread at the small end of the pipe or work in order for the chasers to clear it.

If a short thread is desired the trip assembly 57, 16 and 58 is moved out away from the die chasers.

If the die is used to cut a full length of thread, say 6 inches before tripping and is set, as above described, for threading such full length of thread, and a 5" length of thread is required, this trip plate 16 is moved forwardly from the above setting one inch. Thus, the end of the pipe or work when it contacts the plate 16 will move one inch toward the chaser before contacting the chaser. Therefore, the die will use one inch expanding action before starting to thread and the die will trip after five inches of thread have been cut.

Resetting the die

Resetting the die in one way is obtained by a lever or fork that can be inserted in the ring 29 at a point near the block 41. By means of this fork or lever, the yoke or ring 29 can be moved toward the front of the die and with it the block 41 until the slot 40 in this block 41 is in position to permit the trigger 37 to move therewith by the pressure of the spring 39. This forms an outside resetting means.

The die can also be reset by having a yoke or pad brought up against the ring 30 until the block 41 is moved into position to permit the trigger 37 to move into the slot.

The two springs 42' move the inner slide forwardly in the die as soon as the pipe or work is removed from the die.

This die is also constructed so that it can be reset by inside means. As the pipe is removed from the die when the threading action is completed, the springs 42' move the inner slide forward until a lug 60 fastened to the inner slide by the screw 61 and pin 62, comes in contact with a lug 63 fastened to the block 41 by screws 64. At this time a rod or any suitable means can be inserted through the back of the die to move the inner slide further forward, whereupon the lug 60 will move the lug 63 forwardly with the block 41 until the slot in the block 41 has been moved into position to permit the trigger 37 to enter, and maintain the block in position until tripped as hereinbefore described.

It is to be understood that, by describing in detail herein any particular form, structure or arrangement, it is not intended to limit the invention beyond the terms of the several claims or the requirements of the prior art.

Having thus explained the nature of my invention and described a way of constructing and using the same, although without attempting to set forth all of the forms in which it may be made or all of the modes of its use, I claim:

1. A die comprising a body, an axially shiftable slide therein and a sliding sleeve thereon, radially shiftable chasers carried by the body and connected with the sleeve for radially shiftable movement thereof, and a plurality of piv-

otal connecting members between the slide and sleeve, each of said members having a plurality of pivotal connections and a pivotal connection with each other, whereby a relative difference in movement is effected between the slide and sleeve to effect a tapered threading of the work.

2. A die comprising a body, an axially shiftable slide therein and a sliding sleeve thereon, radially shiftable chasers carried by the body and connected with the sleeve for radially shiftable movement thereof, and a plurality of pivotal connecting members between the slide and sleeve, each of said members having a plurality of pivotal connections and a pivotal connection with each other, whereby a relative difference in movement is effected between the slide and sleeve to effect a tapered threading of the work, said pivotal connecting members also having pivotal connection with the body.

3. A die comprising a body, an axially shiftable slide therein and a sliding sleeve thereon, radially shiftable chasers carried by the body and connected with the sleeve for radially shiftable movement thereof, and a plurality of pivotal connecting members between the slide and sleeve, each of said members having a plurality of pivotal connections and a pivotal connection with each other, whereby a relative difference in movement is effected between the slide and sleeve to effect a tapered threading of the work, said pivotal connecting members also having a pivotal connection with the body.

4. A die comprising a body, an axially shiftable slide therein and a sliding sleeve thereon, radially shiftable chasers carried by the body and connected with the sleeve for radially shiftable movement thereof, and a plurality of pivotal connecting members between the slide and sleeve, each of said members having a plurality of pivotal connections and a pivotal connection with each other, whereby a relative difference in movement is effected between the slide and sleeve to effect a tapered threading of the work, each of said pivotal connecting members also having a pivotal connection with the body, one of said last pivotal connections stationary relative to the body during the thread cutting operation and movable at the end of the thread cutting to shift the cutters to permit removal of the work.

5. A die comprising a body, an axially shiftable slide therein and a sliding sleeve thereon, radially shiftable chasers carried by the body and connected with the sleeve for radially shiftable movement thereof, and a plurality of pivotal connecting members between the slide and sleeve, each of said members having a plurality of pivotal connections and a pivotal connection with each other, whereby a relative difference in movement is effected between the slide and sleeve to effect a tapered threading of the work, each of said pivotal connecting members also having a pivotal connection with the body, one of said last pivotal connections stationary relative to the body during the thread cutting operation and movable at the end of the thread cutting to shift the cutters to permit removal of the work, said last pivotal connection also axially adjustable to effect radial adjustment of the chasers.

6. A die comprising a body, an axially shiftable slide therein and a sliding sleeve thereon, radially shiftable chasers carried by the body and connected with the sleeve for radially shiftable movement thereof, and a plurality of piv-

otal connecting members between the slide and sleeve, each of said members having a plurality of pivotal connections and a pivotal connection with each other, whereby a relative difference in

5 in movement is effected between the slide and sleeve to effect a tapered threading of the work, each of said pivotal connecting members also having a pivotal connection with the body, one of said last pivotal connections radially adjust-
10 able to effect adjustment of the taper of the thread to be cut.

7. A die comprising a body, an axially shift-
able slide therein and a sliding sleeve thereon, radially shiftable chasers carried by the body
15 and connected with the sleeve for radially shift-
able movement thereof, a plurality of pivotal connecting members between the slide and sleeve, each of said members having a plurality of piv-
otal connections and a pivotal connection with
20 each other, whereby a relative difference in movement is effected between the slide and sleeve to effect a tapered threading of the work, and tripping means for tripping the chasers upon completion of the threading operation.

25 8. A die comprising a body, an axially shift-
able slide therein and a sliding sleeve thereon, radially shiftable chasers carried by the body and connected with the sleeve for radially shift-
able movement thereof, a plurality of pivotal
30 connecting members between the slide and sleeve, each of said members having a plurality of piv-
otal connections and a pivotal connection with each other, whereby a relative difference in movement is effected between the slide and sleeve
35 to effect a tapered threading of the work, and tripping means both automatically and manu-
ally operative for tripping the chasers upon completion of the threading operation.

9. A die comprising a body, an axially shift-
40 able slide therein and a sliding sleeve thereon, radially shiftable chasers carried by the body and connected with the sleeve for radially shiftable movement thereof, a plurality of pivotal connecting members between the slide and sleeve, each
45 of said members having a plurality of pivotal connections and a pivotal connection with each other, whereby a relative difference in movement is effected between the slide and sleeve to effect a tapered threading of the work, tripping means for tripping the chasers upon completion of the threading operation, and means for adjusting the chasers radially.

50 10. A die comprising a body, an axially shift-
able slide therein and a sliding sleeve thereon, radially shiftable chasers carried by the body
55 and connected with the sleeve for radially shift-
able movement thereof, a plurality of pivotal connecting members between the slide and sleeve, each of said members having a plurality
60 of pivotal connections and a pivotal connection with each other, whereby a relative difference in movement is effected between the slide and sleeve to effect a tapered threading of the work, tripping means for tripping the chasers upon completion of the threading operation, and a plurality of independently operative means for adjusting the chasers radially.

65 11. A die comprising a body, an axially shift-
able slide therein and a sliding sleeve thereon, radially shiftable chasers carried by the body
70 and connected with the sleeve for radially shift-
able movement thereof, a compound pivotal connecting means between the slide and sleeve whereby a relative difference in movement is ef-
75 fected between the slide and sleeve to effect a

tapered threading of the work, tripping means for tripping the chasers upon completion of the threading operation, and a plurality of independently operative means for adjusting the chasers radially, one of said last means comprising 5 radially shiftable members carried by the body, each having a series of cam slots therein and cam rods carried by the sleeve and co-acting with said cam slots.

12. A die comprising a body, an axially shift-
able slide therein and a sliding sleeve thereon, radially shiftable chasers carried by the body and connected with the sleeve for radially shift-
able movement thereof, a plurality of pivotal connecting members between the slide and sleeve, each of said members having a plurality
15 of pivotal connections and a pivotal connection with each other, whereby a relative difference in movement is effected between the slide and sleeve to effect a tapered threading of the work, tripping means for tripping the chasers upon completion of the threading operation, and a plurality of independently operative means for adjusting the chasers radially, one of said last means comprising means for changing the location of 25 one of the pivotal points of one of said pivotal connecting members.

13. A die comprising a body, an axially shift-
able slide therein and a sliding sleeve thereon, radially shiftable chasers carried by the body
30 and connected with the sleeve for radially shift-
able movement thereof, a plurality of pivotal connecting members between the slide and sleeve, each of said members having a plurality
35 of pivotal connections and a pivotal connection with each other, whereby a relative difference in movement is effected between the slide and sleeve to effect a tapered threading of the work, tripping means for tripping the chasers upon completion of the threading operation, and ad-
40 justable means for controlling the taper of the work.

14. A die comprising a body, an axially shift-
able slide therein and a sliding sleeve thereon, radially shiftable chasers carried by the body
45 and connected with the sleeve for radially shift-
able movement thereof, a plurality of pivotal connecting members between the slide and sleeve, each of said members having a plurality
50 of pivotal connections and a pivotal connection with each other, whereby a relative difference in movement is effected between the slide and sleeve to effect tapered threading of the work, tripping means for tripping the chasers upon completion of the threading operation, and a 55 plurality of independently adjustable means for controlling the taper of the work.

15. A die comprising a body, an axially shift-
able slide therein and a sliding sleeve thereon, radially shiftable chasers carried by the body
60 and connected with the sleeve for radially shift-
able movement thereof, a plurality of pivotal connecting members between the slide and sleeve, each of said members having a plurality
65 of pivotal connections and a pivotal connection with each other, whereby a relative difference in movement is effected between the slide and sleeve to effect tapered threading of the work, tripping means for tripping the chasers upon 70 completion of the threading operation, and a plurality of independently adjustable means for controlling the taper of the work, one of said last means comprising a radially movable holding member carried by the body and a pivotal con- 75

nection between said holding member and one of said pivotal connecting members.

16. A die comprising a body, an axially shift-
able slide therein and a sliding sleeve thereon,
5 radially shiftable chasers carried by the body
and connected with the sleeve for radially shift-
able movement thereof, a plurality of pivotal
connecting members between the slide and
sleeve, each of said members having a plurality
10 of pivotal connections and a pivotal connection
with each other, whereby a relative difference
in movement is effected between the slide and
sleeve to effect tapered threading of the work,
tripping means for tripping the chasers upon
15 completion of the threading operation, and a
plurality of independently adjustable means for
controlling the taper of the work, one of said
last means comprising a holding member carried
by the body, a plurality of positioning means
20 carried thereby, and a pivotal connection be-
tween said holding member and one of said pivotal
connecting members and carried by one of
said positioning means.

17. A die comprising a body, an axially shift-
able slide therein and a sliding sleeve thereon,
radially shiftable chasers carried by the body and
connected with the sleeve for radially shiftable
movement thereof, a plurality of pivotal connect-
ing members between the slide and sleeve, each
30 of said members having a plurality of pivotal
connections and a pivotal connection with each
other, whereby a relative difference in move-
ment is effected between the slide and sleeve to
effect a tapered threading of the work, tripping
35 means for tripping the chasers upon completion
of the threading operation, and a plurality of
independently adjustable means for controlling
the taper of the work, one of said last means
comprising a plurality of pivotal holding means,
40 each adapted for connecting said slide and one
of said pivotal connecting members.

18. A die comprising a body, an axially shift-
able slide therein and a sliding sleeve thereon,
radially shiftable chasers carried by the body
and connected with the sleeve for radially shift-
able movement thereof, a plurality of pivotal
connecting members between the slide and
sleeve, each of said members having a plurality
50 of pivotal connections and a pivotal connection
with each other, whereby a relative difference in
movement is effected between the slide and
sleeve to effect a tapered threading of the work,
tripping means for tripping the chasers upon
55 completion of the threading operation, and ad-
justable means for controlling the length of
thread of the work.

19. A die comprising a body, an axially shift-
able slide therein and a sliding sleeve thereon,
radially shiftable chasers carried by the body
and connected with the sleeve for radially shift-
able movement thereof, a plurality of pivotal
connecting members between the slide and sleeve,
each of said members having a plurality of pivotal
65 connections and a pivotal connection with
each other, whereby a relative difference in move-
ment is effected between the slide and sleeve to
effect a tapered threading of the work, tripping
means for tripping the chasers upon completion
70 of the threading operation, and adjustable means
for controlling the length of thread of the work
and comprising an axially movable work engag-
ing member.

20. A die comprising a body, an axially shift-
able slide therein and a sliding sleeve thereon,
75 radial v shiftable chasers carried by the body

and connected with the sleeve, a transversely
extending member pivotally connected with the
slide and with the body, a circular member
pivotally connected with the sleeve and with the
body, and means pivotally connecting said mem-
bers whereby pivotal movement of said first mem-
ber effects pivotal movement of said second mem-
ber thereby to effect a relative difference
in movement between the slide and sleeve where-
by a tapered threading of the work is obtained.

21. A die comprising a body, radially shiftable
chasers carried thereby, a pair of members shift-
able axially relative to said body and to each
other, one of said members adapted to engage
the work, the other of said members adapted
15 to co-act with the chasers to effect a tapered
threading of the work, and a plurality of pivotal
connecting members for said axially shiftable
members, each of said connecting members hav-
ing a plurality of pivotal connections and a
20 pivotal connection with each other, whereby the
movement of one of said axially shiftable mem-
bers relative to the body will effect movement of
the other of said axially shiftable members rela-
tive to the body and said first axially shiftable
25 member.

22. A die comprising a body, an axially shift-
able slide therein and a sliding sleeve thereon,
radially shiftable chasers carried by the body
and connected with the sleeve, means pivotally
30 connected with the body and slide, and means
pivotally connected with the body and sleeve and
having a pivotal connection with said first means
spaced from all other of said pivotal connections
whereby movement of the slide is transmitted to
35 the sleeve in the ratio of the difference between
the spacing of the pivotal points of connection
of the first means with the body and slide, and
its connection with the body and the second
means multiplied by the ratio of the difference
40 between the pivotal points of connection of the
second means with the body and sleeve, and its
connection with the body and first means there-
by to effect a tapered threading of the work.

23. A die comprising a body, an axially shift-
able slide therein and a sliding sleeve thereon,
radially shiftable chasers carried by the body and
connected with the sleeve, a transversely extend-
ing member pivotally connected with the slide
and with the body, a circular member pivotally
50 connected with the sleeve and with the body,
and means pivotally connecting said members
whereby pivotal movement of said first member
effects pivotal movement of said second member
thereby to effect a relative difference in move-
55 ment between the slide and sleeve whereby a
tapered threading of the work is obtained, the
pivotal points of said pivotal connecting means
movable in lines parallel to the axis of the
die.

24. A die comprising a body, an axially shift-
able slide therein and a sliding sleeve thereon,
radially shiftable chasers carried by the body
and connected with the sleeve, a transversely ex-
tending member pivotally connected with the
slide and with the body, a circular member piv-
otally connected with the sleeve and with the
body, and means pivotally connecting said mem-
bers whereby pivotal movement of said first mem-
ber effects pivotal movement of said second mem-
ber thereby to effect a relative difference in move-
ment between the slide and sleeve whereby a
tapered threading of the work is obtained, the
pivotal points of said pivotal connecting means
movable in lines parallel to the axis of the die,

- one of said pivotal points stationary relative to the body during the thread cutting operation and movable relative thereto upon completion of the thread cutting operation to effect disengagement 5 of the cutters from the work.
25. A die comprising a body, an axially shiftable slide therein and a sliding sleeve thereon, radially shiftable chasers carried by the body and connected with the sleeve, a transversely extending member pivotally connected with the slide and with the body, a circular member pivotally connected with the sleeve and with the body, and means pivotally connecting said members whereby pivotal movement of said first member 10 effects pivotal movement of said second member thereby to effect a relative difference in movement between the slide and sleeve whereby a tapered threading of the work is obtained, the pivotal points of said pivotal connecting means 15 movable in lines parallel to the axis of the die, one of said pivotal points stationary relative to the body during the thread cutting operation and movable relative thereto upon completion of the thread cutting operation to effect disengagement 20 of the cutters from the work, and means for effecting said last movement.
26. A die comprising a body, an axially shiftable slide therein and a sliding sleeve thereon, radially shiftable chasers carried by the body and connected with the sleeve for radially shiftable movement thereof, and a compound pivotal connecting means between the slide and sleeve whereby a relative difference in movement is effected between the slide and sleeve to obtain 25 a tapered threading of the work, said compound pivotal connecting means comprising a lever pivotally connected to the body and slide and a yoke pivotally connected to the body and sleeve and having pivotal connection with the lever.
27. A die comprising a body, an axially shiftable slide therein and a sliding sleeve thereon, radially shiftable chasers carried by the body and connected with the sleeve for radially shiftable movement thereof, a compound pivotal connecting means between the slide and sleeve whereby a relative difference in movement is effected between the slide and sleeve to obtain a tapered threading of the work, said compound pivotal connecting means comprising a lever pivotally 30 connected to the body and slide and a yoke pivotally connected to the body and sleeve and having pivotal connection with the lever, means for adjusting the chasers radially comprising means for moving a pivotal connection of said yoke,
- means for controlling the taper of the work comprising means for moving a pivotal connection of said lever, and means for controlling the length of thread of the work, said last means comprising a movable member secured to said axially shiftable slide. 5
28. A die comprising a body, an axially shiftable slide therein and a sliding sleeve thereon, radially shiftable chasers carried by the body and connected with the sleeve for radially shiftable movement thereof, and a compound pivotal connecting means between the slide and sleeve and including a pivoted yoke encircling said body whereby a relative difference in movement is obtained between the slide and sleeve to effect 10 a tapered threading of the work. 15
29. A die comprising a body, an axially shiftable slide therein and a sliding sleeve thereon, radially shiftable chasers carried by the body and connected with the sleeve for radially shiftable movement thereof, and a compound pivotal connecting means between the slide and sleeve whereby a relative difference in movement is effected between the slide and sleeve to obtain a tapered threading of the work, said compound 20 pivotal connecting means comprising a pivoted lever and a pivoted yoke. 25
30. A die comprising a body, an axially shiftable slide therein and a sliding sleeve thereon, radially shiftable chasers carried by the body and connected with the sleeve for radially shiftable movement thereof, and a compound pivotal connecting means between the slide and sleeve whereby a relative difference in movement is effected between the slide and sleeve to obtain 30 a tapered threading of the work, said compound pivotal connecting means comprising a pivoted lever and a pivoted yoke pivotally connected to each other. 35
31. A die comprising a body, an axially shiftable slide therein and a sliding sleeve thereon, radially shiftable chasers carried by the body and connected with the sleeve for radially shiftable movement thereof, and a compound pivotal connecting means between the slide and sleeve whereby a relative difference in movement is effected between the slide and sleeve to obtain a tapered threading of the work, said compound pivotal connecting means comprising a lever and a yoke, one pivotally connected to the body and slide 40 and the other pivotally connected to the body and sleeve and having a pivotal connection with each other. 45
